[57] CLAIM

The ornamental design for a combination sliding door
and rail cover, substantially as shown.

DESCRIPTION

FIG. 1 is a perspective view of the combination sliding
door and rail cover;

FIG. 2 is a front elevation view of the same;

FIG. 3 is a perspective view of the cover;

FIG. 4 is a top elevation view of the same;

FIG. 5 is a rear elevation view of the same; and

FIG. 6 is a side elevation view of the same.

The broken lines shown in FIGS. 1 and 2 are for illustrative
purposes only and form no part of the claimed
design.

FIG. 2

FIG. 1

FIG. 3

FIG. 4

FIG. 6

FIG. 5
